US00D937061S

(12) **United States Design Patent** (10) **Patent No.:** **US D937,061 S**
(45) **Date of Patent:** **** Nov. 30, 2021**

(54) **HYGROTHERMOGRAPH**

(71) Applicant: **Shenzhen Intellirocks Tech. Co., Ltd**,
Shenzhen (CN)

(72) Inventors: **Cheng Gong**, Shenzhen (CN); **Tong Li**,
Shenzhen (CN); **Wenlong Wu**,
Shenzhen (CN)

(73) Assignee: **Shenzhen Intellirocks Tech, Co., Ltd**,
Shenzhen (CN)

(**) Term: **15 Years**

(21) Appl. No.: **29/731,879**

(22) Filed: **Apr. 20, 2020**

(51) LOC (13) Cl. **10-04**

CLAIM

The ornamental design for a hygrothermograph, as shown and described.

DESCRIPTION

FIG. 1 is a first perspective view of a hygrothermograph showing the new design;

FIG. 2 is a second perspective view of the hygrothermograph showing the new design;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

1 Claim, 8 Drawing Sheets
